UNITED STATES PATENT OFFICE.

SAMUEL A. BENNER, OF PITTSBURGH, PENNSYLVANIA.

METHOD OF ROLLING METAL SECTIONS.

1,226,942.

Specification of Letters Patent. Patented May 22, 1917.

Application filed May 20, 1914. Serial No. 839,872.

To all whom it may concern:

Be it known that I, SAMUEL A. BENNER, a citizen of the United States, and resident of Pittsburgh, in the county of Allegheny and State of Pennsylvania, have invented a new and useful Improvement in Methods of Rolling Metal Sections; and I do hereby declare the following to be a full, clear, and exact description thereof.

10 My invention relates to the manufacture of integral wrought metal structural members or sections, and is particularly concerned with methods of rolling or rolling and pressing such members or sections. In 15 the art of metal rolling and pressing, as at present practised, the character and size of the shapes which may be commercially rolled or pressed are limited by the kind and size of the rolling mills or presses, and 20 it is found that many desired shapes and sizes of wrought sections cannot be commercially manufactured by the usual methods by reason of these limitations.

The object of my invention therefore is 25 to overcome these difficulties by the peculiar method of carrying out the rolling or rolling and pressing operations herein described.

The invention consists in its broader 30 aspects in first designing a section of a form that may be produced in rolling mills of the usual standard construction, and thereafter subjecting it to finishing rolling or pressing operations to bring it to its final 35 shape.

In the following description of the methods of forming selected embodiments of the invention the terms "flange" and "web" are used for convenience to denote certain parts, 40 in the sense in which these terms are usually understood in the art of rolling sections of metal. That is to say, by "flange" is meant that part of the section produced by a groove cut in the plane of the diameter of a 45 rolling mill roll, and by a "web" is meant that part of the section produced by faces formed in the plane of the length of the roll.

With this explanation, the invention may 50 be stated to consist, in its primary form, in the rolling of a section comprising a flange with a web at an angle thereto on each side thereof, one web being joined into the side of the flange, and the other web joined 55 into the base of the flange by means of a turn in said latter web, and then bending

the latter web at the turn thereof, by a flattening operation in rolls or presses or otherwise. A further development of the invention consists in rolling two or more of these 60 primary sections together and integrally, either by joining the straight webs together, or by joining the turned webs together, or by joining a straight web to a turned web.

By way of illustration, I have shown in 65 the accompanying drawings various unusual sections produced by my improved method, in which Figure 1 is a cross section of one form of rolled section embodying my invention, certain modifications being in dotted 70 outlines. Fig. 2 is a diagrammatic view indicating the shape of the rolls by which the full line section shown in Fig. 1 may be produced. Fig. 3 is a view similar to Fig. 1 showing said section bent to its final 75 shape. Fig. 4 is a view similar to Fig. 1 of a modified form of section. Figs. 5, 6 and 7 are views indicating diagrammatically the various steps in bringing such section with the addition of flanges at the outside edges of the outside webs to its finished shape. Fig. 8 is a view of the finished 80 shape of said section. Fig. 9 is a view similar to Figs. 1 and 4 of another modification. Fig. 10 shows the section Fig. 9 85 bent to its final shape. Fig. 11 is a view of a further modification and Fig. 12 is a view of the section Fig. 11 bent to its final shape.

The first step in my improved process consists in the forming of a section of a shape 90 which may be produced in rolling mills of usual standard construction. Such section is indicated in Fig. 1 in which it is shown to comprise a flange 1 which as indicated in Fig. 2, may be formed by a groove 3 in the plane of the diameter of the rolling mill roll 4. Into one side of the flange 1 is joined a web 5 formed by the faces 6 and 7 of the rolls 4 and 8. It will be seen by inspection of Figs. 1 and 2 that the web 5 joins into the side of the flange 1 at an angle thereto. At the opposite side of the flange is a second web 9 which is formed by the faces 10 and 11 of the rolls 4 and 8 respectively. This web is joined into the base of the flange 1 105 at 12 by a turn in said web at 13. Thus is formed the blank shown in full lines in Fig. 1. The webs of this blank may be provided with any desired number of flanges such as end flanges or intermediate flanges or both. 110 The blank thus formed may be subjected to a second rolling or pressing or bending op-

eration which will bend the web 9 at its turn 13 and thus bring the web 9 into alignment with the flange 1 forming the section illustrated in Fig. 3.

5 In the embodiment of the invention shown in Fig. 4 the preliminary section or blank comprises a pair of flanges 16—16, a central web 17, the opposite ends of which are joined into the bases of the flanges 16, respectively, by the turns 18—18. Also this blank includes the outside webs 19—19 each of which is joined into a side of each of the flanges 16, respectively. This blank is then subjected to one or more rolling or pressing 10 operations to bring it into final form as indicated in Figs. 5, 6 and 7, in which 20 indicates a shaping die or roll of a press or a rolling mill roll said member having a flat bottom face 21 and the inclined faces 22. The 15 width of the face 21 is just sufficient to enter between the flanges 16—16 which serves to bend the web 17 at the turns 18—18 to the shape shown in Fig. 6. The blank is then subjected to a further shaping between the 20 members 23 and 24 which serve to flatten the web 17 and the flanges 16—16 into one plane and to bring the webs 19—19 into angular relation with respect to said main web (in this case to bring them at right angles 25 thereto.) Thus is formed the shape of section shown in Fig. 8. The section Fig. 9 consists of the flanges 25—25, the intermediate web 26 joined into the sides of said flanges 25—25, and the webs 27 joined into 30 the bases of the flanges 25—25, respectively, by the turns 28. This blank is then subjected to pressing or bending operations similar to those heretofore described and brought finally into the form Fig. 10. The 35 section Fig. 11 comprises the pair of flanges 29—29 one having a web 30 joined into its base by a turn 31 and having a web 32 joined into its side which web is joined into the base of the other flange 29 by a turn 33 and the last mentioned flange has a web 34 joined 40 into its side as shown. This blank may be subjected to bending or pressing operations to flatten the webs at the turns 31 and 33 respectively, to bring the section into the 45 form in Fig. 12.

50 It will be seen that the blank Fig. 4 may be considered to consist of duplicate sections such as that shown in Fig. 1 in which the webs 9 are joined together in one plane. The form of blank shown in Fig. 9 may be considered to consist of duplicate sections similar to Fig. 1 in which the webs 5 are joined in one plane. The form of blank shown in Fig. 11 may be considered to consist of duplicate sections similar to Fig. 1 in which the web 5 of one is joined to the web 9 of the other in one plane.

55 It will be obvious from an examination of the several sections or blanks here shown 60 that many permutations or combinations of

the section Fig. 1 may be formed to produce blanks which may subsequently be bent into forms not heretofore possible by means of methods of rolling or pressing heretofore known.

70 While in the preferred practice of the invention the blank is first formed by a rolling operation and then is completed by rolling or pressing operations, it is to be understood that in certain cases the original or preliminary form of the blank might be formed by a pressing operation, and that the final form may be secured by one or more subsequent pressing or rolling operations as the case may be.

75 The sections produced by my improved method, particularly those of the form shown in Fig. 8, and the modifications thereof, may be used as car bolsters, center, end or side sills, car side stakes, railway cross-ties, structural girders, structural columns, bridge floors, and in smaller form for window sash, the sections being rolled of steel 80 preferably with the channel sides with or without the inturned flanges.

85 What I claim is:

90 1. The method of manufacturing wrought integral metal sections which consists in rolling a section, comprising a flange with a web at an angle thereto on each side thereof, one web joined into the side of the flange, and the other web joined into the base of the flange by means of a turn in said latter web, and then bending the latter web at the turn thereof by a flattening operation.

95 2. The method of manufacturing wrought integral metal sections which consists in rolling a section comprising a plurality of flanges with a web on each side of each of said flanges and at an angle thereto, certain 100 of said webs being joined into the sides of said flanges, respectively, and certain of said webs being joined into the bases of said flanges, respectively, by means of a turn in each of said latter webs and then bending 105 the latter webs at the turns thereof, respectively, by a flattening operation.

110 3. The method of manufacturing wrought integral metal sections which consists in rolling a plurality of flanges, each flange 115 having a web at an angle thereto on each side thereof, the web between the flanges being joined to the latter into the bases thereof by means of turns in said web, and then bending each web having the turn 120 therein, at the turn, by a flattening operation.

125 4. The method of manufacturing wrought integral metal sections, which consists in rolling a section comprising a flange with a web at an angle thereto on each side thereof, one web joined into the side of the flange, and the other web joined into the base of the flange by means of a turn 130 in said latter web, and then bending the 135

latter web at the turn thereof by a flattening operation, one or both of said webs having a flange at its outer edge.

5. The method of manufacturing wrought integral metal sections which consists in rolling a section comprising a flange with a web at an angle thereto on each side thereof, one web joined into the side of the flange, and the other web joined into the base of the flange by means of a turn in said latter web, and then bending the latter web at the turn thereof by a flattening operation, one or both of said webs having a flange intermediate its edges.

15. 6. The method of manufacturing wrought integral metal sections which consists in rolling a section comprising a pair of flanges joined together by an intermediate web, the edges respectively of said web being joined into the bases of said flanges by a turn in the web, each of said flanges having a web joined into the outer side thereof, and then bending said intermediate web at its turns by a flattening operation, to bring said intermediate web and said flanges into one plane, and to bring said side webs into planes parallel with each other.

25. 7. The method of manufacturing wrought integral metal sections which consists in rolling a section comprising a pair of flanges joined together by an intermediate web, the edges respectively of said web being joined

into the bases of said flanges by a turn in the web, each of said flanges having a web joined into the outer side thereof, and then 35 bending said intermediate web at its turns by a flattening operation to bring said intermediate web and said flanges into one plane, and to bring said side webs into planes parallel with each other, said side 40 webs having flanges at their outer edges to form with the first mentioned flanges laterally opening channel members.

8. The method of manufacturing wrought integral metal sections which consists in 45 rolling a section comprising a pair of flanges joined together by an intermediate web, the edges respectively of said web being joined into the bases of said flanges by a turn in the web, each of said flanges having a web 50 joined into the outer side thereof, and then bending said intermediate web at its turns by a flattening operation to bring said intermediate web and said flanges into one 55 plane, and to bring said side webs into planes parallel with each other, said side webs having also inturned flanges at their outer edges.

In testimony whereof, I the said SAMUEL A. BENNER have hereunto set my hand.

SAMUEL A. BENNER.
